RECORDER MECHANISM FOR ELECTRICAL
ROLL CALL OR VOTING APPARATUS

Charles F. Thompson, Dumbarton, Va.

Application June 25, 1936, Serial No. 87,273

2 Claims. (Cl. 271—53)

My invention relates to electrical roll-call or voting systems, such as are used by legislative and other deliberative bodies, and consists of a new type of high speed vote recording machine.

In the past, commercially practical vote recording machines operating on the commutator principle, recorded each member's vote consecutively, and therefore took an undesirably long period of time to operate. The present application discloses a vote recording machine that can be built to simultaneously record any desired number of votes, and therefore operates in a fraction of the time heretofore required by devices of this character.

This application is one of a series of applications relating to a voting system in which the membership is divided into a number of divisions for high speed vote recording purposes. This application is a continuation in part of my application, Serial No. 77,839, filed May 4, 1936. The recording machine of this new system records each division of members in a separate column of names on the record card. The underlying principle used by this recording machine is that of rapidly feeding a paper card, by a step by step movement, beneath a line of recording solenoids, so that a vote in each division, or each column of names across the card, is automatically and simultaneously recorded, each time the paper card is stepped forward.

Among the objects of this invention are:

To provide a vote recording machine capable of simultaneously recording one member's vote in each column of names, and thus operate in a fraction of the time heretofore required by old style recording devices which recorded but one member's vote at a time.

To provide a vote recording machine of the utmost simplicity, in which a record card is merely fed under a line of recording solenoids.

To provide a vote recording machine mechanically separated from the commutator, so that a single commutator may drive several recording machines, or none at all, as the case may be; and to provide means for keeping the recording circuits in electrical balance for spark elimination purposes, regardless of the number of recording machines in use.

To provide a vote recording machine of such small size, and light weight, and so few electrical connections, that it is portable and capable of being plugged-in or disconnected, at a moment's notice.

To provide a vote recording machine that may be constructed so inexpensively, voting bodies

can afford to install them for the press, party leaders, and other authorized persons, in addition to the official recorder at the clerk's desk.

I attain the above objects by mechanism illustrated in the accompanying drawings, in which—

Fig. 1 is a front sectional view of my recording machine.

Fig. 2 is a side sectional view of my recording machine, on line 2—2 of Fig. 1.

Fig. 3 is a partial side sectional view of my recording machine, on line 3—3 of Fig. 1.

Fig. 4 shows my recorder is capable of embossing or printing the record card as well as perforating it.

Fig. 5 discloses a top sectional view of my recorder, on line 5—5 of Fig. 1.

Fig. 6 shows a sample of the record card used.

Fig. 7 shows a fragmentary section of my recorder on line 7—7 of Fig. 5.

Fig. 8 shows a theoretical wiring diagram of my recorder.

Fig. 9 discloses a structure using an alternative paper feed mechanism.

Fig. 10 shows a top view of the structure illustrated in Fig. 9.

Fig. 11 discloses the construction of the paper feed cylinder shown in Figs. 9 and 10.

The recorder herein illustrated is of very flexible construction. As indicated in Fig. 4 it may be adapted to emboss or print the record card when these methods are preferred to perforating.

Likewise the card may be fed out of the recorder in the direction of entry, or in the opposite direction. The card may be either pushed or pulled through the recorder, and by either sprocket wheels or friction wheels, and the paper feed mechanism may or may not be locked against over-throw on each feeding impulse, as desired. These alternative constructions provide a flexibility in manufacturing, but do not depart from the spirit and purpose of my invention.

Figs. 1 to 7 inclusively, disclose my recorder in its most simple form. Following the wiring diagram shown in Fig. 8, a construction is illustrated in Figs. 9 to 11 inclusively, embodying the various alternative constructions in a single structure.

Similar numerals refer to similar parts throughout the several views.

Considering first Figs. 1 to 7 inclusively, it will be seen that the basic structure of my recorder consists of a casting constituting a base 12, having on its top surface, two members 13 and 14, to guide the record card. A plate 15 preferably of iron, is fastened on top of projecting members

5

13 and 14 by the threaded ends 16 of the four corner posts 17, 18, 19 and 20, thereby providing a passage for the record card between elements 12, 13, 14 and 15. Recorders may be built to record any number of voting divisions, but the recorder disclosed is for three voting divisions. Therefore mounted on top of plate 15 is a row of nine twin solenoids for recording the Aye, Not-voting and Nay votes of the three divisions, in the three corresponding columns on the record card. First division, or column, Aye votes are recorded by solenoids 21, Not-voting votes by solenoids 22, and Nay votes by solenoids 23. Second division, or column, Aye votes are recorded by solenoids 24, Not-voting votes by solenoids 25, and Nay votes by solenoids 26. Third division, or column, Aye votes are recorded by solenoids 27, Not-voting votes by solenoids 28, and Nay votes by solenoids 29. The stationary cores 30 of all solenoids 21 to 29 inclusive, are riveted in plate 15 by their shanks 31. The solenoids 21 to 29 inclusively are held in place over the cores 30, by the top plate 32, which contains entry holes for the base tubes 33 of each solenoid, as well as four corner holes 34 for passage of the threaded ends 34 of the four corner posts 17, 18, 19 and 20. Two plungers such as 35 are riveted to a common yoke 36, and such an assembly is mounted in each of the twin solenoids 21 to 29. The yokes 36 are each tapped to receive an adjustable recording rod 37, which may be locked in position by its nut 38. Each recording rod 37 passes through a bushing 39 mounted in plate 15, so it may perforate a hole when the twin solenoid is energized. A die such as 40 containing hole 41 is placed directly beneath each recording rod 37, and the lower end of each rod 37 is reduced in size to fit holes 41, as indicated at 42. A passage hole 52 is provided in top plate 32 for each recording rod 37 passing through it.

The rods 37 may be adapted to emboss rather than perforate, as shown by rod 37a in Fig. 4, which contains a recording end 42a of concave or other desired embossing shape, and a suitable corresponding die 40a to match. The rods 37 may be also adapted to print rather than perforate, as shown by rod 37b in Fig. 4, which contains a recording end 42b that may be plain as shown, or equipped with any desired letter, word or character. For printing, a ribbon, indicated at 43 passes through a channel in bottom of plate 15, indicated at 44, under the line of recording rods such as 37b; and a rubber pad 46b, also passing under the line of recording rods 37b replaces dies 40.

The yoke 36 of each twin solenoid, with its recording rod 37 and two plungers 35 attached thereto, is normally pushed upward by spring 45 until yoke contacts stop plate 46, with nut 38 passing through hole 53. Four corner holes are provided on stop plate 46 for passage of threaded ends 34 of the four corner posts 17, 18, 19 and 20. Collars such as 47 on the threaded ends 34 of posts 17, 18, 19 and 20, are so proportioned in length as to provide proper travel for the solenoid plungers 35. Nuts indicated at 48 on corner post ends 34 lock the stop plate 46 against collars 47.

The nine twin solenoids 21 to 29 inclusively, and connected parts mentioned, are covered by housing 49, which rests on members 13 and 14, and which retains its location by snugly fitting over plate 15. Housing 49 is covered by top 50, which is held in place by cap nuts 51 on the threaded ends 34 of the corner posts 17, 18, 19 and 20.

A sample of the record card is indicated at 54. By lifting handle 5 of hinged plate 56, record card 54 may be inserted through slot composed of members 12, 13, 14 and 15, until its motion is arrested by card stop 57. In this position recording rod 37 of solenoids 21 is above record card position 58, and rod 37 of solenoids 29 is above record card position 59, and the balance of the recording rods 37 are spaced over the various recording positions lying between 58 and 59 on record card 54. It will be noted that plate 56 is hinged by pins 60 and 61 connecting it with blocks 62 and 63. These blocks 62 and 63 also guide the entry of record card 54 in its slot.

The record card 54 is equipped with lines of paper feed holes 64, 65, 66 and 67. When card 54 is inserted in its slot until it contacts card stop 57, and then released, the perforated feed holes 64, 65, 66 and 67 will engage with the sprocket teeth 68 of the sprocket wheels 69, 70, 71 and 72, mounted on shaft 73. When handle 55 is released, hinged plate 56 drops and rests on studs 99, which have sufficient elevation to cause card 54 to pass freely under plate 56 and yet prevent card 54 from becoming disengaged from the sprocket wheels 69, 70, 71 and 72.

Shaft 73 is supported by bearings 74 and 75, and upon shaft 73 are pinned two ratchet wheels 76 and 77, each of which is normally engaged with a detent roller 78. Each roller 78 is supported by arm 79, pivoted at 80, and held in engagement with its ratchet wheel by spring 81. The sprocket teeth 68 on the sprocket wheels 69, 70, 71 and 72 are so proportioned as to feed the record card 54 from one line of names to the next, each time the ratchet wheels 76 and 77 are advanced the space of one tooth, and with this construction, the record card 54 is fed out of the recorder in the opposite direction from which it entered.

A paper feed solenoid is placed in each side of the casting base 12, as indicated at 82 and 83, to actuate ratchet wheels 76 and 77. Each paper feed solenoid 82 and 83 is equipped with an adjustable core 84, threaded into casting 12 for adjustment purposes and locked by nut 85. Front end of each feed solenoid 82 and 83 is supported by a bracket 86, to which is pivoted at 87, the feed lever 88. Each feed lever 88 is attached at 89 to its respective solenoid plunger 94. Motion of each feed lever 88 is controlled in one direction by its stop screw 89, and in the other direction by its solenoid core 84. A feed pawl 90 is pivoted at 91 to each feed lever 88, and held in engagement with its respective ratchet wheel 76 or 77 by its spring 92. Attached to each feed lever 88 is a main spring 93, also attached to the casting base 12, which supplies the energy for feeding the record card 54.

The record card 54 may be fed directly by the feed solenoids 82 and 83 if so desired, but I prefer to feed the record card 54 when said solenoids become de-energized by action of the springs 93, as this permits a more uniform wiper adjustment at the selector, and causes the feed solenoids 82 and 83 to operate at approximately the same time the recording solenoids are operating.

Energization of feed solenoids 82 and 83 causes their respective plungers 94 to be attracted toward their cores 84, moving each feed lever 88 until its respective pawl 90 is in position to engage the next tooth on its corresponding ratchet wheel 76 or 77. When solenoids 82 and 83 become de-energized, springs 93 cause record card 54 to be moved to the next recording position.

In Fig. 8 a wiring diagram is disclosed. Three

voting units are indicated at *a*, *b* and *c*. Voting unit *a* is in the first voting division, and connected to the first contactors in division A of the selector, which control the first column solenoids of the recorder. Voting unit *b* is in the second voting division and connected to the first contactors in division B of the selector, which control the second column solenoids of the recorder. Voting unit *c* is in the third voting division and connected to the first contactors in division C of the selector, which control the third column solenoids of the recorder.

The voting units *a*, *b*, and *c* are shown connected to positive battery with their respective blades 96 resting on Not-voting contactors 97. If blades 96 were thrown to right they would cause Aye votes to be recorded, or if thrown to left they would cause Nay votes to be recorded.

The selector section for feeding the record card 54 is indicated at *H*, where the wiper is in position to feed successive impulses to the paper feed solenoids 82 and 83.

All recorder solenoids, including the paper feed solenoids 82 and 83, are connected through switch 25 *K* to common negative battery, and therefore as long as switch *K* is in the closed position illustrated, all said recorder solenoids will become energized in accordance with the impulses received from the selector. Three of the nine recording solenoids, and the paper feed solenoids 30 82 and 83, will be energized each time the selector wipers contact a new set of operating contactors, and as said wipers leave said contactors, the record card 54 will be moved one recording position 35 forward by action of springs 93. It will be observed when switch *K* is opened, an inductance coil 98 is substituted for each twin recording solenoid, and also for the pair of paper feed solenoids, so the electrical characteristics of the recording 40 circuits will remain constant for spark elimination purposes regardless of whether the recorder is connected for operation. The same system of substituting inductances for recorder solenoids can be used where several recorders are installed 45 in parallel and switches are used to individually connect or disconnect them.

The basic principle of the structure described consists of perforating a line of holes across the card, or otherwise recording a line of marks of 50 some character across the card, and then stepping the card into a new position for another recording operation. However, as mentioned, without departing from the scope of my invention, the paper feed mechanism may be built in a variety of constructions. For instance, friction 55 wheels may replace the sprocket wheels, or the direction of feed may be reversed, or the card pushed instead of pulled, and the feed mechanism may be locked against over throw if desired. These alternative features are disclosed in a 60 structure shown in Figs. 9 to 11, inclusively, which will be now described.

Figs. 9 to 11 inclusively disclose a base 12a, having mounted upon it the dies 40a, the card 65 slot and paper guide members 13a and 14a, and the two blocks 62a and 63a; and having mounted within it the usual paper feed solenoids 82a and 83a, each having its core 84a threaded into base 12a and locked by nut 85a, and each supported 70 by its bracket 86a.

The direction of feed in this structure is the reverse to that previously described, the record card being fed in the same direction it enters the slot. This direction of feed is necessary when the record cards are printed in the form of a

roll of tape, and may be used also with individual record cards such as 54. It will be observed the feed mechanism pushes the record card through the slot instead of pulling it through as formerly described. 5

While the structure shown in Figs. 9 to 11 inclusively may be equipped with sprocket wheels for feeding the card, the said structure is herein illustrated with friction wheels for that purpose. Sprocket feed is desirable for long columns 10 of names, or when the record cards are printed in the form of a roll of tape, but friction feed is entirely suitable for my recorder when using individual record cards having comparatively few names to the column. 15

In the structure shown in Figs. 9 to 11 inclusively, the record card is pushed through the slot by a long feed cylinder 100, extending approximately the full width of the record card, which may have its exterior smooth, or suitably lined 20 and grooved for added frictional effect. Feed cylinder 100 has a ratchet wheel such as 101 permanently fastened to each end. The shaft 102 upon which the feed cylinder and ratchet assembly revolves, is fastened non-movably in the 25 shaft holes of projections 103 and 104 of base 12a. The feed cylinder projects through an elongated hole 105 in base 12a so it may contact the paper. Swinging on shaft 102 is a pawl frame 106 for each of the ratchet wheels 101. 30 Each pawl frame carries a pawl 107 pivoted to the frame 106 by pin 108, and held in engagement with its respective ratchet wheel 101 by spring 109. Each solenoid plunger indicated at 110 is equipped with a flanged head 111 to hold paper feeding spring 112. Pivoted at 114 to each pawl frame 106, is a link 113. The other end of link 113 is fastened to its respective solenoid plunger 110, which is fitted with a slot 115 and pivot pin 116 to receive it. Motion of the pawl frame 106 is limited in one direction by the adjustable solenoid core 84a, and in the other direction by the adjustable stop screw 117. Straddling link 113 is shown a lever 118, supporting detent roller 119, which is held in engagement with the 45 teeth of the ratchet wheel 101 by the spring 120. 40

It will be seen that the teeth on ratchet wheels 101 are of different shape than those illustrated in the previous structure. The purpose of shaping the ratchet teeth as shown at 101, is to permit a safety feature to be incorporated in the construction, when so desired, for preventing possible overthrow of the feed cylinder 100 when the feed solenoids 82a and 83a are de-energized. For this purpose each link 113 is equipped with 50 a tooth 121, designed to lock cylinder 100 and its ratchet wheels 101 against rotation until the solenoids 82a and 83a have been energized, and designed further to move back into the path of the ratchet wheel teeth, before the spring 112 55 has succeeded in moving pawl 107 to the limit of its stroke. 60

When my recorder is constructed to push the card through the slot, and individual record cards are used, it becomes necessary to provide 65 a retractable card stop. However this construction permits use of a feature not otherwise possible, of providing a buckling space in the card slot between the feed mechanism and the recording mechanism. This feature would permit the card to buckle rather than tear if the feed operation ever commenced before the recording 70 operation was completed. When a buckling space is provided in the card slot it becomes necessary to block that buckling space when the 75

card is inserted. Otherwise the card could buckle after hitting its stop and thereby record incorrectly. The mechanism accomplishing these results will now be described.

5 Rollers of rubber or other material must be provided to press the record card on the feed cylinder 100. Three such rollers are illustrated at 122, 123 and 124. Each said roller is pivoted by a shaft such as 126, in an individual roller frame such as 127. Each frame 127 is under individual spring tension. A shaft 128 is supported between the blocks 62a and 63a and pinned in said blocks as indicated at 129. The individual frames 127 holding rollers 122, 123 15 and 124 are swung on shaft 128 and separated by collars such as 130. Springs such as 131, having their centers pinned to shaft 128 as indicated at 132, and having their ends overlap the sides of the roller frames 127, provide the necessary 20 tension for rollers 122, 123 and 124. These said rollers may however be simultaneously lifted for the purpose of inserting a record card by the U-shaped frame 133, which is also pivoted on shaft 128, and which is fitted with a finger lift 25 134.

Pivoted to each side of frame 133, as indicated at 135, is a link 136, having two limiting stops 137 and 138. Said links pass through suitable holes in base 12a, but the limiting stops 30 137 and 138 strike the base 12a when frame 133 is raised or lowered. The lower ends of links 136 are connected at 139 to a cradle frame 140 inside the base 12a. Cradle frame 140 is hinged at 141 and 142 and carries a shaft 143 holding 35 card stop arms 144 and 145, which project through holes in the base 12a and thus stop the card when finger lift 134 is raised and the card inserted. Card stops 144 and 145 are adjustable on the shaft 143, and are arranged so they are removed from the path of the card as soon 40 as the rollers 122, 123 and 124 have clamped the record card to the feed cylinder 100. The card can thus be fed in the same direction in which it was inserted.

45 When a card is inserted it is placed between the two links 136 and guided between blocks 62a and 63a, and between guides 13a and 14a, until it strikes the card stops 144 and 145. In this position the card lays over the buckling space 146, which is located between the feed mechanism and the recording mechanism. During insertion of the card the cradle frame 140 is raised, and a portion thereof 140a, fills and blocks the buckling space 146, so the card cannot buckle into said space when it strikes stops 144 50 and 145 during insertion. After insertion of the card has been arrested by stops 144 and 145,

the finger lift 134 is released, which lowers cradle frame 140, removing portion 140a thereof from the buckling space 146, and withdrawing stops 144 and 145 as soon as the card is clamped between rollers 122, 123, 124, and feed cylinder 100. 5 The card is now free to buckle if the feeding operation overlaps the recording operation, and will automatically straighten itself when the recording operation ends.

Any number of the features shown in Figs. 9 10 to 11 inclusively may be incorporated in the structure described in Figs. 1 to 7 inclusively. It should be understood no feed holes such as 64, 65, 66 and 67 are necessary when friction feed is used; and also that the commutator or 15 selector wipers shown in Fig. 8 move together, as is well illustrated by the application of this series covering that device.

What I claim as new and desire to secure by Letters Patent of the United States is as follows: 20

1. In a machine for recording on a record card, a base having a passage for the card, a projectible stop operably mounted in said base, card feed means including pressure means adapted to hold the card in operative engagement therewith, actuating means for projecting said stop and simultaneously lifting said pressure means for inserting a record card in the passage in said base in predetermined position for engagement by said feed means, said stop 30 being withdrawn into said base with the release of said pressure means for operation of said feed means, said base being provided with a recording position and a longitudinal opening constituting a buckling space for the record card 35 in said passage intermediate said recording position and the card feed means, and a bar member connected with said actuating means and movable in conjunction with said stop, said bar member being adapted to close said buckling space with the stop in projected position for the 40 introduction of a record card into the passage in said base.

2. In a machine for recording on a record paper, a base having a passage for the paper 45 provided with a recording position, paper feed mechanism for advancing the paper to said recording position, said base having an opening therein intermediate said recording position and said feed mechanism and constituting a buckling space in said passage for said paper, and means 50 including a blocking member projectible into said opening for closing the buckling space for insertion of the record paper into the passage in said base.
